ICE BUCKET

George Biondi, Via del Parione 6, Florence, Italy, and
Renzo Fanucchi, Via Provenciale, Lucehese 6, Pescia,
Italy

Continuation-in-part of design application Ser. No. 24,539,
Aug. 17, 1970, which is a continuation of design application
Ser. No. 14,788, Dec. 4, 1968, both now abandoned. This application Mar. 3, 1971, Ser. No. 120,793

Claims priority, application Italy June 5, 1968

Term of patent 3½ years

Int. Cl. D7—02

U.S. Cl. D7—78

Fig. 1

Fig. 3

Fig. 4

Fig. 5

Fig. 6

FIG. 1 is a front elevational view of an ice bucket showing our new design;

FIG. 2 is an end elevational view thereof taken in the direction of line II—II on FIG. 1;

FIG. 3 is a rear elevational view thereof taken in the direction of line III—III on FIG. 2;

FIG. 4 is an end elevational view thereof taken in the direction of line IV—IV on FIG. 3, the handle being in a tilted position;

FIG. 5 is a plan view thereof taken in the direction of line V—V on FIG. 3; and

FIG. 6 is a plan view thereof taken in the direction of line VI—VI on FIG. 3.

This application is a continuation-in-part of design application Ser. No. D. 24,539, filed Aug. 17, 1970 which is a streamlined continuation of design application Ser. No. D. 14,788, filed Dec. 4, 1968, both now abandoned.

We claim:

The ornamental design for an ice bucket, substantially as shown and described.
